MEANS FOR INSTALLING AND REMOVING
FLOW VALVES

Kenneth C. Howard, Fort Worth, Tex., and Harold E. McGowen, Jr., and Howard H. Moore, Jr., Bunkie, La., assignors to Sid W. Richardson Inc., Fort Worth, Tex., a corporation of Texas

Application June 24, 1948, Serial No. 34,954

8 Claims. (Cl. 166—1)

1

This invention relates to flow valves for oil wells and has reference to a means for installing and removing valves and the like in a string of well tubing.

Flow valves in oil wells have delicate mechanisms and often require removal from the well for repairs or adjustments. Since these valves are attached to the well tubing, it has been heretofore necessary to remove the entire string of tubing in order to make such repairs or adjustments, which removal operation was costly in that considerable time was expended during the removal operation.

The primary object of the present invention is to provide a means for the installation and removal of flow valves without removing the well tubing to which said valves are attached during operation.

In accordance with our invention a flow valve installing or removing tool, either with or without an attached flow valve, depending on whether the valve is to be installed in or removed from its seat, is lowered through a well tubing provided with a lateral offset portion having an opening therein for the flow valve, the tool being lowered to the level of the offset portion and then deflected laterally by any suitable means into the offset portion of the tube, and the flow valve seated in the opening of the offset portion where the valve is being installed, or the tool engaged with the valve where the valve is to be removed, after which the tool is rotated in one direction or the other to seat or remove the valve, following which seating or unseating step the tool, without the valve in the case of a valve installing operation, or with the valve attached in the case of a valve removing operation, is drawn up through the tubing to the surface of the ground.

The invention will be more readily understood by reference to the accompanying drawings and the following detailed description.

Figure 1 is a vertical sectional view of a special flow valve sub or section within a string of well tubing and showing a flow valve installed therein, together with an electrical tool for installing and removing the said valve.

Figure 2 is an enlarged elevational view of the tool illustrated in Figure 1, and showing the same in extended jarring position.

Figure 3 is an enlarged broken elevational view of the lower end of the tool illustrated in Figure 2, and particularly showing the electro-magnet, motor, and socket, and jar mechanisms of the tool.

2

Figure 4 is a lateral sectional view of the socket taken on lines 4—4 of Figure 3.

Figure 5 is a vertical sectional view of a modified form of the invention wherein the flow valve is installed for operation in alignment with the axis of the well tubing.

Figure 6 is an enlarged broken elevational view of the lower end of a tool, similar to the one illustrated in Figure 2, engaged on the upper end of the valve illustrated in Figure 5.

Figures 7 and 8 are enlarged transverse sectional views taken on lines 7—7 and 8—8, respectively, of Figure 5.

Figure 9 is an enlarged broken sectional and elevational view of the lower end of the tool illustrated in Figure 6 and showing the same engaged on the adapter at the upper end of a flow valve, such as illustrated in Figure 5.

Figure 10 is a vertical sectional view of a flow valve sub, similar to the one illustrated in Figure 1, and showing a mechanical means for shifting a tool for installing or removing a flow valve.

Figure 11 is an elevational and sectional view of the form of the invention illustrated in Figure 10 and showing the tool positioned for actuating a trigger of the mechanical shifting means illustrated in Figure 10.

Figure 12 is a transverse sectional view taken on lines 12—12 of Figure 11.

Figures 13 and 14 are taken on lines 13—13 and 14—14, respectively, of Figure 10.

Figure 15 is an enlarged broken and elevational view of the shifting mechanism illustrated in Figure 10, and showing one of the shifting arms in extended position.

Figure 16 is a transverse sectional view taken on lines 16—16 of Figure 15.

Figure 17 is an enlarged sectional view of a portion of Figure 15 and showing the trigger mechanism for releasing one of the actuating arms and shifting the tool laterally with respect to the axis of the well tubing.

Figure 18 is an elevational and sectional view of the socket and ratchet mechanism which, during operation, is threadedly engaged in the lower end of the shifting mechanism illustrated in Figure 15.

Figure 19 is a transverse sectional view taken on lines 19—19 of Figure 18.

Figure 20 is a broken elevational view of the ratchet mechanism of the device illustrated in Figure 18.

Figure 21 is a plan view of a selector ring forming a part of the mechanism illustrated in Figure 20.

Figure 22 is an elevational view of an adapter to be secured at the upper ends of a conventional flow valve whereby the various forms of the invention may be engaged by the tools herein illustrated for installing and removing the said valves.

Figure 23 is a vertical sectional view of the valve supporting arrangement illustrated in Figure 5.

Figure 24 is a transverse sectional view taken on lines 24—24 of Figure 1.

The form of the invention illustrated in Figure 1 includes a special valve sub or inserted section of the well tubing 1 which is downwardly and outwardly tapered along one side, as at 2, and which tapered portion is provided with a substantially horizontal bottom 3 having a downwardly and inwardly tapered and threaded hole 4 for threadedly engaging an adapter 5 into which a conventional flow valve 6 is threaded. In operation, the sub 1 is installed in a string of tubing 7 in a well, and it is to be understood that many sub units 1 and valves 6 are employed for raising oil to the earth's surface. The adapter 5 is provided with a central opening 8 for communicating the valve 6 with the interior of the sub 1. A sectional view of the adapter 5 is illustrated in Figure 22.

Within the tapered side 2 of the sub 1 there is a multiple of spaced parallel splines 9 integral with the said side, as shown in Figure 24, and which splines are adapted to receive corresponding splines 10 around the circumference of an electric shifting tool 11.

As shown in Figure 3, the upper end of the tool 11 is provided with a tubular jar 12 having an inwardly directed annular flange 13 at its lower end. The upper end of the jar 12 is secured to a cable 14 which is raised and lowered from above the earth's surface. The cable 14 carries insulated wires 15 for operating an electro-magnet 16 in the upper end of the tool 11 and a reversible motor 17 in the lower end of the tool.

The shifting tool 11 is slidably connected with the jar 12 by means of a mandrel 18 slidably extending into the said jar, which mandrel is provided with an outwardly directed annular flange 19 for engagement with the internal flange 13 of the jar 12. The electric wires 15 extend downwardly through the mandrel 18 and into the tool 11 where they are suitably connected with the magnet 16 and the motor 17. Since the wiring is a matter of conventional practice, the same is not herein described in detail.

The shaft 20 of the motor 17 is disposed downwardly along the central axis of the tool 11 and is provided with suitable bearings 21 at its lower end where it supports a pinion 22 for engagement with a planetary gear 23. Any suitable gear reduction mechanism may be employed and therefore the gear construction is not described in detail. The referred to gear arrangement 22, 23, drives a socket 24 rotatably mounted in the lower end of the tool 11, and which socket is adapted to engage and frictionally secure the upper end of the valve adapter 5. The referred to adapter includes vertical splines 25 along its outer surface, and which splines are notched, as at 26, near their upper end. Correspondingly, the socket 24 is provided with vertical recesses 27 to receive the splines 25 of the adapter 5, and the said recesses are provided with springs 28, secured in the upper end of the socket 24 by a screw 24a, which springs are formed to engage the notches 26 in the adapter splines 25. A 75

plate of soft iron 29 is secured outwardly of the tapered portion 2 of the non-magnetic sub 1 whereby the tool 11 may be moved toward the same when the electro-magnet 16 is energized. The bosses 30 around the upper end of the tool 11 are for aligning the tool when the latter is shifted against the tapered portion 2 of the sub 1.

The operation of the described form of the invention is carried out by lowering the tool 11 downwardly through the tubing 7 and into the upper end of the sub 1. By energizing the electro-magnet 16 as the tool approaches an expanded area the tool 11 is moved laterally toward the soft iron plate 29. The tool is then further lowered by the cable 14, with the tool sliding against the inner surface of the said inclined portion 2. When the splines 10, which are pointed at their ends, reach the internal splines 9, it may be necessary to jar the tool 11 into place by raising and lowering the cable 14 and operating the jar mechanism 12 which coacts with the tool supporting mandrel 18. When the socket 24 at the lower end of the tool 11 first contacts the upper end of the adapter 5, it may be necessary to slightly rotate the said socket by actuating the motor 17 in order that the socket recesses 27 may properly receive the splines 25 on the valve adapter 5. By then energizing the motor, the adapter may be unscrewed from the bottom 3 of the inclined portion 2 of the sub 1, and by raising the cable 14 the valve 6, held by the springs 28 and the adapter 5, may be raised upwardly through the tubing 7 to the earth's surface.

The valve 6 may be reinstalled by attaching the adapter 5 and valve 6 in the socket 24, where the springs 28 engage the recesses 25 in the adapter splines 25. The tool is then lowered into the sub 1 and the electro-magnet 16 is energized, causing the tool 11 to move laterally toward the soft iron plate 29. The tool 11 is then lowered downwardly along the inside surface of the tapered portion 2 of the sub 1 where the splines 10 on the tool 11 engage the splines 9 in the said tapered portion. The motor 17 is then rotated in a direction to cause the adapter 5 to become threadedly engaged in the tapped hole 4 in the horizontal bottom 3 of the tapered portion 2 of the sub 1.

The form of the invention illustrated in Figures 5, 6, 7, 8, and 23, is for the operation of a conventional flow valve 6 in axial alignment with the tubing 7. This form of the invention includes a straight tubular sub 31 for threaded engagement within a string of tubing and is provided with a bypass 32 around the installed said valve. The valve 6, which has an inlet 6a near its lower end, is provided with a sealing arrangement at its upper and lower ends, and which arrangement includes upper and lower packers 33 and 34, pairs of opposing conical slips 35 and 36 received within each end of each of the said packers, and a slidable tubular spacer 37 between the inner slips 35 and 36. It will be noted in Figures 5 and 23 that the spacer 37, which is spaced from the valve 6, is provided with an opening 38 so as to provide for the passage of oil to the said valve. Similarly, the straight sub 31 is provided with a corresponding opening 39 for allowing oil outwardly of the sub 31 to reach the spacer opening 38.

The adapter 5a for the last described form of the invention is similar to the previously described adapter 5 and has corresponding numbers for corresponding parts, but differs in that threads are provided in the splines 25 and below the notches 26 in the said splines. The lower end

of the adapter 5a threadedly receives the conventional flow valve 6. An outwardly projecting flange 40 is secured to the lower end of the valve so as to engage the outer face of the lowermost conical slip 36. Above the uppermost conical slip 35, there is a nut 41 threadedly engaged on the adapter 5a.

The tool 42 (Fig. 6) for installing the last described arrangement of valves and packers is similar to the one described for installing the first described form of the invention, but is different in that the electromagnet 16 is eliminated, and the socket 43 extends downwardly below the springs 28 where it is shaped to receive and engage the nut 41 on the adapter 5a.

The last referred to tool 42 is provided with the previously described splines 10 around its surface which are adapted to engage splines 44 within the upper end of the tubular sub 31.

The last described valve and packer arrangement is installed by detachably securing the upper end of the adapter 5a in the springs 28 at the lower end of the tool 42. The arrangement is then lowered through the tubing 7 to a position within the tubular sub 31 and between the upper and lower internal openings in the bypass 32. The tool 42 is provided with a motor, not shown, similar to the one previously described, which motor may be rotated to draw the uppermost and lowermost conical slips 35 and 36 toward each other. By reason of the spacer 37 around the valve and between the intermediate slips 35 and 36 of the upper and lower packers 33 and 34, both of the said packers are caused to expand and locate the valve and packer assembly in the described position. By reason of the spring engagement of the tool socket 24, the tool 42 may be raised and released, leaving the valve assembly in place after the packers have been expanded to hold the valve in place. Similarly, the valve assembly may be removed by lowering the tool 42 into a position where the socket 24 and spring 28 engage the upper end of the adapter 39. By reversing the motor and loosening the conical slips 35 and 36, the valve may be raised upwardly through the tubing 7 to the earth's surface.

The form of the invention shown in Figure 10 has to do with a mechanical means for shifting a tool assembly laterally of the central axis of the tubing 7 for installing and removing a valve 6 in a manner similar to the first described form of the invention. The present form includes a jar 45 secured to the lower end of the cable 14. Beneath the jar 45 there is a shifting mechanism 46 which is slidably and extensibly connected with the said jar by means of linking arms 47 joined at their upper ends where they are inter-connected in the manner of a chain with similar joined depending arms 48 at the lower end of the jar 45. The body of the shifting tool 46, which is substantially cylindrical in shape, is provided with multiple longitudinal flutes 49 which receive shifting arms 50 (see Figure 15), which are pivotally secured at their upper ends and within the upper ends of the flutes 49. Within each flute 49 and near the upper end thereof, there is an outwardly extending spring 51 for moving each arm 60 outwardly. The lower end of each arm 50 is provided with a downwardly and inwardly directed arcuate spring 52 which in closed position is received within the lower end of the flute 49. The lower end of the arm 50, above the last described spring 52, is provided with an inwardly and upwardly directed integral hook 53 for coaction with a trigger mechanism, shown in detail in Figure 17, comprised

of a latch 54 pivotally mounted at its center within an opening 55 in the body of the shifting tool 46. Transverse pins 56 through the said body pivotally support the latches 54. One end of each latch 54 is provided with a hook 57 adapted to engage the arm hook 53. The end of each latch 54 opposite its hook 57 is operated by a trigger 58 which is pivotally secured at one end on pins 59 horizontally positioned through the body of the shifting tool 46. Each trigger 58 has a notched recess 60 adapted to engage the end of the latch 54 opposite its hook 57 when the trigger 58 is in its down position and the latch is in its raised position, as shown by dotted lines in Figure 17 and in full lines in Fig. 15. The upper central edge of each latch 54 is provided with a spring 61 which bears against the edge of the trigger 58 opposite the trigger notch 60.

Beneath the shifting mechanism 46, and threadedly secured thereto, there is a ratchet operated socket assembly 62, illustrated in Figures 18 through 21, which includes a tubular body 62 having the previously described splines 10 there-around, and threads 63 at its upper end to engage internal threads 64 in the lower end of the shifting mechanism 46. The axial center of the body 62 is cylindrically hollow, as at 65, where it receives the flanged upper end 66 of a helically fluted mandrel 67. The lower end of the cylindrical cavity 65 is provided with an inwardly positioned annular shoulder 68 to engage the flange 66. The lower end of the body 65 is counterbored to receive a ratchet collar 69 having square teeth 70 around its upper periphery. The ratchet collar 69 is retained by a ferrule 71 threadedly engaged on the lower end of the body 62. The outer lower surface of the body 62 is recessed to receive a rotatable selector ring 72 which is also held in place by the ferrule 71. As particularly shown in Figures 19 and 21, the selector ring 72 is provided with inwardly projecting pins 73 which pass inwardly through horizontal slots 74 in the body 62 where they selectively and tiltably position a pawl 75 (Fig. 20) which is adapted to engage the teeth 70 of the collar 69 at one end thereof and to bear against an end of the horizontal slot 74 in the body 62 at the other end of the pawl. The pawl 75 is retained against lateral displacement by the outer surface of the mandrel 67, and the inner surface of the body shoulder 68. The ratchet collar 69 is provided with integral inwardly directed projections 76 which engage the spiraled grooves 77 in the surface of the mandrel 67. Thus, the position of the pawl 75, which may be tilted in either direction by means of the selector ring 72, controls the direction of rotation of the mandrel 67 when the body 62 is reciprocated. The lower end of the mandrel 67 is provided with a socket 78, welded or otherwise secured thereto, having flutes 79 therein and a transversely disposed ring 80 loosely mounted in an annular groove 81 in the said socket. The purpose of the ring 80 is to frictionally engage the notches 26 in the adapter 5, whereas the last referred to flutes 79 are adapted to engage the splines 25 in the said adapter.

Referring now to Figures 10 and 11, the last described form of the invention is provided with a sub 82 having an outwardly tapered wall along one side, as at 83, and a substantially horizontal bottom 84 at the lower end of the latter. Tubing 7 is threadedly engaged in the upper and lower ends of the sub 82. Near the upper end of the sub 82 and above the outwardly projecting wall there is a recess 85 having an inwardly directed

shoulder 86 adapted to receive one of the triggers 58 of the mechanical shifting tool 46. The bottom 84 of the outwardly directed portion 83 of the sub 82 threadedly receives the described adapter 5 having a conventional flow valve 6 attached to the lower end thereof.

The operation of the last described form of the invention is as follows: the shifting mechanism 46 and its attached assemblies are lowered through the tubing 7 to a level where one of the triggers 58 is moved outwardly, by reason of the spring 61, and into the sub recess 85. See Figure 11. By raising the cable slightly, the trigger 58 is moved relatively downward and thus releases the opposing shifting arm 50, causing the shifting mechanism 46 and the attached ratchet tool 62 to move against the inner wall of the tapered portion 83 of the sub 82. The assembly is then further lowered, whereupon the splines 10 of the tool 62 engage internal splines 87 in the tapered portion of the sub 82. See Figure 13. As shown in Figure 10, the last referred to splines 87 are relatively long to accommodate a reciprocal movement imparted to the tool 62 which is carried out by means of the cable 14 and the jar assembly 47 and 48. By selectively setting the selector ring 72, the socket 73 may be rotated in either direction for installing and removing the adapter 5 and its attached flow valve 6. The direction of rotation is determined above the ground before inserting the assembly in the well. When withdrawing the assembly, the pivot action of the trigger 58 assumes the downward position illustrated by dotted lines in Figure 17.

The described form of the invention is not restrictive, but may be made in many ways within the scope of the appended claims.

What is claimed is:

1. In combination with a well tubing having a vertical main bore, said tubing including one or more flow valve receiving sections each having a portion laterally offset from the vertical main bore and provided with a flow valve seat in the offset portion, and means, including a shifting tool adapted to be lowered from the top of the tubing to the level of a selected section, for selectively seating or removing a flow valve in or from its seat within a selected receiving section, said shifting tool being provided with means for moving said tool and its appendages laterally within the offset portion of the selected section.

2. The combination as set forth in claim 1, wherein the shifting tool is provided with re-

versible rotary means for engaging and rotating a flow valve in setting or removing the same.

3. The combination as set forth in claim 2 wherein the reversible rotary means comprises a ratchet operated socket assembly.

4. The combination as set forth in claim 1 wherein a jar is operatively connected with the shifting tool.

5. The combination as set forth in claim 1 wherein the laterally off-set portion of each flow valve receiving section is provided with substantially vertical parallel guide flanges adapted to coat with splines carried by the shifting tool.

6. The combination as set forth in claim 1 wherein a flow valve seat is formed in a flat base portion of each of the flow valve receiving sections.

7. The combination as set forth in claim 6 wherein the flow valve seat is tapered and threaded to receive a correspondingly formed flow valve adapter.

8. The combination as set forth in claim 1 wherein a flow valve adapter is removably mounted in the flow valve seat, and a flow valve is carried by the adapter below the level of the seat, said adapter being provided with a central passage connecting the interior of the flow valve with the interior of the receiving section.
